[57] ABSTRACT

A refrigerated display case includes an open front permitting customer access to the products contained therein and rear doors permitting access for restocking. An inner curtain of refrigerated air is circulated across the open front and adjacent surfaces forming a portion of the display case to refrigerate the contents therein. The case includes an air inlet extending along the lower front of the case for drawing cooled air therein which is then circulated rearwardly and discharged upwardly adjacent the exterior surface of the rear doors to prevent condensation thereon. The air stream adjacent the doors is then circulated over the top of the case and across the front of the case to form a guard curtain adjacent and outside the inner curtain of refrigerated air.

FIG. 5.

REFRIGERATED DISPLAY CASE**BACKGROUND OF THE INVENTION**

The present invention relates to a refrigerated display case of the type employing multiple air curtains extending across an open front.

In refrigerated display cases of the type which employ a curtain of refrigerated air extending across an open front, an air intake extending along the lower edge of the front of the case in alignment with the air curtain is typically employed to collect the stream of refrigerated air. With such a system, a portion of the cold air forming the curtain tends to mix with adjacent ambient air which is cooled thereby and falls over the front of the case into the aisle. This mixing action which results in the loss of some of the refrigerated air not only reduces the efficiency of operation of the case, it also is frequently a cause of discomfort to a consumer selecting products from the case. The removal of cooled air from the aisle in front of a refrigerated display case with a blower has been suggested, but the cooled air so removed has merely been exhausted.

Open front refrigerated display cases frequently include glass access doors at the rear of the case for allowing restocking and the like. The cases typically are aligned along one end of a store thereby forming a wall, with the rear doors of the case communicating with a room of the retail outlet behind the refrigerated display case. The glass doors can become fogged and/or frosted due to condensation, particularly when the room behind the case is not air conditioned and is relatively warm and humid as during summer months. To reduce the condensation problem, some systems have employed defrosters which force ambient or heated air adjacent the doors to evaporate the condensation. Although useful in providing defrosting, the air so employed is not further utilized.

SUMMARY OF THE INVENTION

The refrigerated display case of the present invention solves the dual problem of cooled air spilled in an aisle and the condensation of moisture on glass access doors at the rear of the refrigerated display case in a unique manner by drawing in the cooled aisle air and forcing this cooler air adjacent the exterior surface of the glass doors. The air so circulated can be recirculated across the open front of the refrigerated display case to form a guard curtain.

By employing the cool spilled air which is recirculated around the case, the efficiency of operation of the refrigeration system of the case is improved since the circulated spilled air is considerably cooler than the ambient air. It therefore forms a barrier to reduce heat transfer across the surfaces and open front of the case. Single pane glass access doors can be employed in place of the more expensive multiple thickness type. In the event that the display case abuts an air conditioned room at the rear of the case, the recirculated air, which is relatively cool, can eliminate condensation on the doors without loading the air conditioning system for the room behind the case as can occur with conventional defrosting systems employing ambient or heated air, especially when several cases are used in an installation.

Refrigerated display cases embodying the present invention include an air inlet extending along the lower

front of the case for removing cool air in an aisle. Means are provided for forcing the cool air drawn inwardly through the inlet adjacent the outside surface of an access door at the rear of the case and for recirculating the air across the open front of the case to form at least a portion of a guard curtain.

It is an object of the present invention to provide an improved method for removing cool air from an aisle in front of a refrigerated display case and for eliminating condensation on access doors at the rear of the case.

An additional object of the present invention is to provide a method of recirculating air spilled over the front of an open front refrigerated display case to form at least a portion of a guard curtain of air.

Another object of the present invention is to provide a refrigerated display case with improved operating efficiency.

Still a further object of the present invention is to provide a refrigerated display case with a recirculated guard curtain of air at least a portion of which is formed from recirculated cool air which spilled over the front of the display case.

An additional object of the present invention is to provide structure for recirculating spilled air adjacent the outer surface of access doors at the rear of a refrigerated display case to eliminate condensation thereon.

These and other objects of the present invention will become readily apparent upon reading the specification together with the accompanying drawings in which:

BRIEF DESCRIPTION OF THE DRAWINGS

FIG. 1 is a front perspective view of a refrigerated display case embodying the present invention;

FIG. 2 is an enlarged fragmentary perspective view of a portion of the refrigerated display case shown in FIG. 1;

FIG. 3 is a rear perspective view of the case shown in FIG. 1;

FIG. 4 is a cross-sectional view of the refrigerated display case illustrating the flow of air therein taken along the section lines IV-IV of FIG. 3; and

FIG. 5 is a fragmentary cross-sectional view of a portion of the case shown in FIG. 4 and taken along the section V-V in FIG. 4.

DETAILED DESCRIPTION OF THE PREFERRED EMBODIMENT

Referring now to FIGS. 1-3, there is shown an open front refrigerated display case 10 having end walls 12, a top cross member 14 and a bottom support member 15 which extends between the end walls 12. The case so formed defines an open fronted compartment 16 with a rear wall 18 including three glass sliding doors 20. Extending vertically between the sliding glass doors 20 are the walls 19 of hollow return air ducts 36 (FIG. 5) which serve also as superstructure supports for the case. Attached to walls 19 in an adjustable fashion, are a plurality of shelves 22 for holding refrigerated products 24 (FIG. 1). In addition to shelves 22, the bottom or bin 26 (FIG. 4) of the compartment is also capable of holding refrigerated products as seen in FIG. 1.

To maintain the low temperature of refrigerated products within compartment 16, an inner curtain 30 of refrigerated air whose path is indicated by the dotted

arrows in FIG. 4, is emitted from a first nozzle 32 extending across the top portion of the front of the display case 10 as best seen in FIGS. 2 and 4. The nozzle can comprise a honeycomb section of conventional design for directing a refrigerated stream of air downwardly across the open front of the case as seen in FIG. 4. Along the top edge of forwardly protruding lip 13 of the display case, i.e., along the lower edge of the opening, there is provided an intake grill 34 extending the length of the case for drawing the refrigerated curtain of air inwardly therein. The air so captured is then recirculated adjacent the bottom shelf 26, the back wall sections 19 and the top wall 25 as seen in FIG. 4.

In addition to the refrigerated air curtain 30, the display case 10 includes a second air curtain 40 indicated in FIG. 4 by the solid line arrows. Curtain 40 is adjacent to and exterior of the refrigerated curtain and is emitted from an outer nozzle 42 extending the length of the refrigerated display case at the top of and exterior to nozzle 32 as seen in FIGS. 2 and 4. Below the lip 13 and toward the upper portion of a front decorative panel 17 forming a portion of the display case 10, there is provided an air inlet 44 in which the cooled air spilled over lip 13 is drawn to remove the air from the access aisle 21 in front of case 10.

The flow paths for the curtains of air 30 and 40 together with the novel structure and unique method of recirculating the outer curtain of air to provide the dual function of removing cooled air from the access aisle and eliminating condensation on the doors is explained in detail with reference to FIGS. 3, 4 and 5.

As seen in FIGS. 4 and 5, the inner refrigerated curtain of air 30 is circulated through the intake grill 34 into a lower plenum chamber 35 and thence into a plurality of ducts 36 extending upwardly adjacent the walls 19 of the rear wall of the case. Ducts 36 communicate between the lower plenum 35 and an upper plenum 37 in which there is provided a blower 38 mounted on a baffle 38' and extending along the width of the case.

Blower 38 forces the return air from ducts 36 into a refrigeration chamber 39 including evaporator coils 39' which refrigerate the recirculated air stream to sub-zero temperatures. The recirculated air is then emitted through nozzle 32 downwardly across the open face of compartment 16 to complete one cycle of recirculation.

Outer curtain 40 is emitted downwardly from nozzle 42 extending across the front of the case and travels downwardly adjacent and outside of the refrigerated curtain 30 across the open face of the case. During its downward travel, curtain 40 is cooled somewhat by the inner curtain and at the lip 13, mixed with whatever portion of the inner curtain that is not drawn inwardly through grill 34. Thus, the air curling over lip 13 is a mixture of the inner and outer curtains 30 and 40 and ambient air and is considerably cooler than the ambient aisle air.

To draw the spilled air within inlet 44 spaced above the floor, one or more fans 46 are mounted in a baffle 47 extending between a rear plenum 48 positioned below each sliding door structure 20. An intake duct 45 communicates between inlet 44 and fans 46. Fans 46 draw the spilled air inwardly through grill 34 and force the air outwardly through nozzles 49 extending across the top of plenums 48. Nozzles 49 are positioned along the bottom edge of doors 20 adjacent the rear surfaces

23 of the doors and extend approximately the full width of the doors.

As seen in FIG. 4, the recirculated spilled air emitted by nozzles 49 is directed against the rear surface 23 of the sliding doors 20 from each of the nozzles 49 and travels upwardly and across the surface of the doors. Air intakes 51 are provided at the top edge of doors 20 opposite nozzles 49. A duct 52 is coupled at one end to intakes 51 and at an opposite end to an intake plenum 53 on top of case 10. Plenum 53 is shaped to accommodate a plurality of fans 56 mounted to a baffle 57 extending across the top of the display case. A solid panel 54 couples baffle 57 to duct 52 such that the fans 56 force the cooled air gathered by intakes 51 through nozzle 42 to form the guard curtain 40 thereby completing the cycle of the recirculated cool air.

The recirculated cool air which travels adjacent rear surface 23 of doors 20 prevents the build-up of condensation on the doors which then can be made from single panels of glass in place of the conventionally employed multiple panels. The efficiency of operation of the display case is greatly enhanced by recirculating the cool air adjacent the outer surface of the rear doors and other surfaces to aid in maintaining the low temperature of the case while simultaneously removing the cool spilled air from the access aisle in front of the case. In addition, the recirculated cool air forms the guard curtain 40.

As will become readily apparent to those skilled in the art, various modifications to the present invention can be made. For example, the recirculation of the spilled air adjacent the outer surface of rear access doors can be used with refrigerated display cases employing a greater number of air curtains formed across the front opening of the case. It may be desirable in some installations to replace the solid panel 54 with an air input grill to permit ambient air at the top of the case to be drawn inwardly and mixed with the cooled air to form the guard jet 40. The apparatus of the preferred embodiment, however, employs a solid panel. Additionally, the particular structure employed to direct the recirculated spilled air across the face of the doors can be modified. These and other obvious modifications, however, will fall within the scope of the present invention as defined by the appended claims.

The embodiments of the invention in which an exclusive property or privilege is claimed are defined as follows.

1. A method of reducing condensation on the exterior of an access door at the rear of an open front refrigerated display case employing a refrigerated curtain of air to maintain the products refrigerated within the case comprising the steps of:

collecting air spilled from said refrigerated curtain over the front of said case;
directing the collected air across the exterior surface of the access door from one edge thereof;
collecting the air at a different edge of the access door; and
recirculating the air collected during the last named collection step across the open front of said refrigerated display case.

2. The method as defined in claim 1 wherein said refrigerated display case employs an inner curtain of refrigerated air and an outer guard curtain and said method includes the additional steps of:

mixing ambient air with air collected during the last named collection step; and exhausting the mixed air across the front of the case to form the guard curtain.

3. A refrigerated display case having a compartment with an open front permitting access to products therein, said case including:

at least one access door in a rear wall thereof; means for forming a curtain of refrigerated air across the open front of said case; means for collecting cool air in an aisle adjacent the front of said case and for discharging the collected air across an exterior surface of said access door from one edge thereof; and means adjacent an opposite edge of said access door for receiving and maintaining the stream of air across said door.

4. The refrigerated display case as defined in claim 3 and further including means for recirculating the received air across the open front of said case.

5. The refrigerated display case as defined in claim 4 wherein said means for forming a curtain of refrigerated air includes a nozzle extending across the open front of said case along the top thereof for directing refrigerated air downwardly; an intake grill extending across the open front of said case near the bottom of the compartment for collecting the refrigerated air curtain; and wherein said means for collecting cool air includes an air inlet extending across said refrigerated display case below said intake grill.

6. The refrigerated display case as defined in claim 5 wherein said means for discharging air across an exterior surface of said access door includes a nozzle extending adjacent said one edge of said access door.

7. The refrigerated display case as defined in claim 6 and further comprising air moving means communicating between said air inlet and said last named nozzle.

8. The refrigerated display case as defined in claim 7 wherein said receiving means comprises an air intake 40 extending along the edge of said access door opposite

said last named nozzle.

9. The refrigerated display case as defined in claim 4 wherein said means for recirculating said received air comprises an outer nozzle extending across said refrigerated display case near the top thereof and air moving means communicating between said receiving means and said outer nozzle.

10. The refrigerated display case as defined in claim 9 and further including means for mixing ambient air 10 with said received air to form a guard curtain of air exhausted across the front of said case exterior to said curtain of refrigerated air by said outer nozzle.

11. A refrigerated display case having a rear access door and an open front permitting customer access to the storage area therein, means for providing a refrigerated air curtain extending across the open front to aid in maintaining the storage area refrigerated whereby the refrigerated air curtain tends to cause cool air to fall into the aisle adjacent said refrigerated display case, and means for circulating air from the aisle adjacent and below said storage area around said refrigerated display case in a path extending in part adjacent the exterior surface of the access door.

12. The refrigerated display case as defined in claim 11 wherein said circulating means includes:

an air inlet extending along said refrigerated display case below the storage area; means for drawing air into said inlet from the aisle adjacent said inlet; and means coupled to said drawing means for directing air from the aisle across the access door from one edge.

13. The refrigerated display case as defined in claim 12 wherein said circulating means further includes: an air intake positioned adjacent an edge of the access door opposite said directing means; and means coupled to said intake for receiving air therefrom and discharging the air across the open front of the refrigerated display case exterior to the refrigerated air curtain.
